CLAIM

The ornamental design for a combined header and sign support housing for a display stand, as shown and described.

DESCRIPTION

FIG. 1 is a front perspective view of a combined header and sign support housing for a display stand showing my new design;

FIG. 2 is a front elevational view thereof;

FIG. 3 is a top plan view thereof;

FIG. 4 is a bottom plan view thereof;

FIG. 5 is a rear elevational view thereof; and,

FIG. 6 is a right side elevational view thereof, with the opposite side being a mirror image.

FIG. 1

FIG. 2

FIG. 3

FIG. 4

FIG. 5

FIG. 6
